UNITED STATES PATENT OFFICE.

CASSIUS H. DARLING, OF WORCESTER, MASSACHUSETTS.

AUTOMATIC DRILLING-JIG.

No. 827,790.

Specification of Letters Patent.

Patented Aug. 7, 1906.

Application filed December 7, 1904. Serial No. 235,872.

To all whom it may concern:

Be it known that I, CASSIUS H. DARLING, a citizen of the United States, residing at Worcester, in the county of Worcester and State of Massachusetts, have invented a new and useful Automatic Drilling-Jig, of which the following is a specification.

This invention relates to an apparatus for handling small parts or pieces.

10 The special object of this invention is to provide an apparatus for automatically feeding and clamping small pieces in position to be drilled.

To this end this invention consists of the 15 drilling-jig and of the combinations of parts therein, as hereinafter described, and more particularly pointed out in the claims at the end of this specification.

In the accompanying drawings, Figure 1 is 20 a side view, partly broken away, of a drilling-jig constructed according to this invention. Fig. 2 is a perspective view showing a small piece or blank clamped in position to be drilled. Fig. 3 is a detail view of some of 25 the pieces which coöperate in holding a blank in place, and Fig. 4 is a detail view of the adjustable guide for the pusher.

In manufacturing many classes of devices—such as firearms, type-writers, sewing-machines, &c.—large numbers of small 30 pieces are used.

In order to drill small duplicate pieces, the present machine-shop practice is to employ different forms of jigs or holders and to manually place the pieces or blanks to be drilled 35 into these holders or jigs.

The especial object of my present invention is to provide a combined jig and feeding apparatus which will handle the pieces or 40 blanks to be drilled automatically, dispensing with the handling of separate pieces during the drilling operation.

Referring to the accompanying drawings and in detail, a drilling-jig constructed according to this invention, as herein illustrated, comprises a base piece or frame 10, having an upright or bracket 11 near one end thereof. Pivoted on the bracket 11 is a bell-crank lever 12. One arm of the bell-crank 45 lever is connected to a vertical link which may be connected to the vertically-moving drill-head or which may be operated in any other desired manner. The other end of the bell-crank lever 12 is connected to a block 15, which has a downwardly-extending pro-

jection sliding in a groove in the base 10. Connected with the block 15 is a rod 16, and fastened to the other end of the rod 16 is a block or slide 17. Replaceably connected with the block or slide 17 is a plunger or 60 pusher 18. The pusher is intended to move back and forth in the space between the cover-plate 19 and the vertically-adjustable feed-table 20. The feed-table 20 can be raised or lowered by means of screws, and the 65 space between the cover-plate and feed-table is adjusted to correspond with the thickness of the piece which is to be fed to the drill. Different plungers or pushers 18 are employed, according to the thickness of the 70 pieces to be drilled, and the end of each plunger or pusher 18 is shaped to correspond with the part to be operated upon, as shown in Fig. 2.

Replaceably fastened upon the cover-plate 75 19 is a reservoir or holder 21, which may contain a stack of blanks or pieces of work W. By means of this construction as a pusher 18 is moved back and forth below the reservoir 21 blanks or pieces of work to be drilled will 80 be successively moved forward over the feed-table and will be carried into engagement with a removable and adjustable stop-plate 23.

Coöoperating with the plunger or pusher 18 is a spring-pressed arm 22, which coöperates 85 with the pusher and stop in clamping a piece of work in place and which also serves to push away a piece of work which has been drilled or bored by the drill D. When a piece of work is clamped in position to be drilled, the 90 spring-pressed arm 22 is preferably swung back to a position at right angles with the stop-plate 23, the swinging motion of the spring-pressed arm being limited by a fixed piece 24. The plunger 18 when moved forward is intended to clamp the piece of work to be acted upon into the angle between the 95 spring-pressed arm 22 and the stop 23. In order to adjust and guide the plunger 18 to secure exactly the desired clamping action, 100 one side of the plunger 18, as shown in Fig. 3, is slightly beveled or inclined, and coöperating with the inclined side of the plunger 18 is an adjustable guide 25, which may consist of two pieces hinged together, as shown in Fig. 105 4, and which guide can be moved to different positions and held in place by means of screws 26. By means of this adjustment the plunger will be guided in its forward movement to crowd the piece or blank to be oper- 110

ated upon accurately into place and into contact with the spring-pressed arm 22 and stop 23, the comparatively small taper of the plunger producing a strong wedging action which will hold the work in place with great firmness while being operated upon.

By means of this construction it will be seen that I have provided a form of drilling-jig which can be adapted to a considerable variety of work by the use of a number of replaceable pusher-plates and by the replacement of different magazines, which may be filled with pieces to be operated upon of different shapes.

15 The magazines for the drilling-jig can be loaded or filled by hand or by automatic machinery—such, for example, as already employed for feeding rivets or other small parts.

I am aware that changes may be made in 20 practicing my invention by those who are skilled in the art without departing from the scope thereof as expressed in the claims, and I do not wish, therefore, to be limited to the construction which I have herein shown and 25 described; but

What I do claim, and desire to secure by Letters Patent of the United States, is—

1. In a construction of the class described, the combination of a feed-table, a pusher for 30 conveying successive pieces over the feed-table, a movable arm which is forced back out of the way while pieces are being drilled, and which has a path of movement at an angle to the path of movement of the pusher and acting to move successive pieces out of the way after they have been drilled, and means for restoring the movable arm to normal position when the pusher is withdrawn.

2. In a construction of the class described, 40 the combination of a feed-table, a magazine, a pusher for conveying successive pieces from the magazine over the feed-table, a spring-pressed arm located in the path of the pusher so as to be deflected thereby and acting to 45 move successive pieces out of the way after they have been drilled.

3. In a construction of the class described, the combination of a support, a cover-plate connected thereto, a feed-table, and means 50 for raising the feed-table to adjust the space between the table and cover-plate.

4. In a construction of the class described, 55 the combination of a feed-table, a pusher conveying successive pieces over the feed-table, a fixed stop, and a side wall located at an oblique angle to the end of the pusher when the parts are in operating position, whereby

a piece to be drilled will be clamped in place from three sides while being operated upon.

5. In a construction of the class described, 60 the combination of a cover-plate, a magazine mounted thereon, a feed-table, and means for raising the feed-table to adjust the space between the cover-plate and feed-table according to the thickness of the parts to be 65 drilled.

6. In a construction of the class described, the combination of a feed-table, stops or abutments on the feed-table, a pusher, the inclined end of which co-operates with the stops 70 or abutments to form a clamp, and inclined means for deflecting the pusher laterally, whereby the end of the pusher will tighten the clamp.

7. In a construction of the class described, 75 the combination of a feed-table, a pusher having an inclined edge, fixed stops or abutments co-operating with the pusher to form a clamp, and an adjustable guide-piece engaged by the pusher to deflect the same laterally to 80 clamp the pieces in place while being drilled.

8. In a construction of the class described, the combination of a feed-table, a pusher conveying successive pieces over the feed-table, a fixed stop, a spring-pressed arm having a path of movement at an angle to that of the pusher, and means for limiting the movement of the spring-pressed arm to a position substantially at right angles to the fixed stop, whereby work may be clamped in position between the inclined end of the pusher, the fixed stop, and the spring-pressed arm. 90

9. In a construction of the class described, the combination of a feed-table, a magazine, a pusher conveying successive pieces from 95 the magazine over the feed-table, a fixed stop, a spring-pressed arm having a path of movement at an angle to the path of movement of the pusher, means for limiting the movement of the spring-pressed arm to a 100 position substantially at right angles to the fixed stop, and means for crowding the pusher laterally to clamp successive pieces of work in place between the inclined end of the pusher, the fixed stop, and the spring-pressed arm. 105

In testimony whereof I have hereunto set my hand in the presence of two subscribing witnesses.

CASSIUS H. DARLING.
